CLAIM

The ornamental design for a tissue holder, as shown and described.

DESCRIPTION

FIG. 1 is a perspective view of a tissue holder showing our new design;

FIG. 2 is a top plan view thereof;

FIG. 3 is a front elevation view thereof;

FIG. 4 is a bottom plan view thereof;

FIG. 5 is a rear elevation view thereof; and,

FIG. 6 is a left side elevation view thereof, the opposite elevation side being a mirror image of the side shown.
